UNITED STATES PATENT OFFICE.

JOHN DUGDILL, OF MANCHESTER, ENGLAND.

ELECTRICAL FITTINGS.

No. 825,199.

Specification of Letters Patent.

Patented July 3, 1906.

Application filed May 22, 1905. Serial No. 261,607.

To all whom it may concern:

Be it known that I, JOHN DUGDILL, electrical engineer, a subject of the King of Great Britain, residing at 305 Oldham road, Failsworth, Manchester, in the county of Lancaster, England, have invented new and useful Improvements in or Relating to Electrical Fittings, of which the following is a specification.

10 My invention relates to electric fittings; and it consists of the combination of a spring reel or bobbin upon which flexible conductors are coiled and from thence led to a lamp or other current-consuming device, a ball-and-socket joint, and a tube or tubes through which the flexible conductors pass to the lamp. The ball-and-socket joint is located between the housing for the spring-reel and the end of the tube. 15 In some cases the spring-reel may be disposed within the ball carried on the end of the tube. By means of the ball-and-socket connection of the tube with the housing for the reel the tube can be readily moved and 20 fixed about a comparatively large area, so that the lamp or other device can be brought to various parts of a work-bench, table, desk, or the like. 25 The ball-and-socket joint provides universal movement for the tube within sufficient range for practical utility, the tube being of any desired length, the end of the tube forming the point from which the flexible conductor emerges and from which the lamp or 30 other device is pendent. In a modified form the tube may be made telescopic, the lower portion being attached to the lamp or the like, so that the height of the lamp is varied by telescoping the lower tube within the upper tube, the spring-reel paying out the conductors or taking up the slack of the same, as required.

35 Figure 1 of the drawings shows one form of my invention in sectional elevation. Fig. 2 is a modification in which the tube containing the flexible conductor is made telescopic. Fig. 3 is a cross-section through the line A B, Fig. 2. Fig. 4 shows in section how the spring-reel may be disposed within the ball. 40 Fig. 5 shows my invention applied to an electrolier. Fig. 6 indicates how the fittings may be attached to a wall, and Fig. 7 shows how the fittings may be carried on a table or floor.

45 Referring to Fig. 1, within the body or housing *a* is mounted in suitable bearings the

spring reel or bobbin *b*. Upon the bobbin *b* are wound the flexible conductors or insulated wires *c*, connected to a lamp or other current-consuming device. The reel or bobbin *b* may be a rotary switch constructed in accordance with an invention for which I have applied for Letters Patent, Serial No. 250,226, or it may simply be a spring-reel with independent switching arrangement of any ordinary or suitable construction. I provide the ball-and-socket joint by means of a sphere or ball *d*, secured upon the upper end of a tube *e*, the spherical socket being obtained partly by the lower part *a'* of the body *a* and partly by the lower portion *f* of a surrounding metallic casing *g*. To bind the ball *d* within the socket sufficiently to permit the tube *e* being retained in any desired position, the outer casing *g* can be adjusted by means of the screws *g'* passing through the flange *g''* and into the pattrass *a''*, a space being left between the flange and the pattrass for this purpose. The flexible conductors pass from the spring reel or bobbin *b* through a conically bored-out plug *b'*, of wood or other suitable material, within the ball *d* and, thence through the tube *e*, the lower end of which is fitted with a bush *e'*, of ebonite or other insulating substance, which will prevent chafing of the wires as the tube is manipulated and the wires are run up and down the tube. It will be obvious from an inspection of the drawings that the tube *e* can be placed and retained at any angle or direction radiating from the ball-and-socket joint within the limits permitted by the size of the opening *f'* of the socket, so as to bring the lamp over any part of a desk, bench, or the like. The height of the lamp is regulated by either pulling down the insulated wires *c*, thus unwinding them from the reel *b*, and coiling up the spring *b''* in the reel, or by lifting the lamp to relieve the wires *c* of its weight when the spring acts to rewind the flexible conductors upon the reel, as will be understood.

50 In the modification shown in Figs. 2 and 3 two tubes, one telescoping within the other, are used. The upper tube *h* is fluted, the extreme edges or peripheries at the upper end being chased to enable it to be screwed into the head *i*, which is screwed to the ball *d*. The lower end of the tube *h* is similarly screw-threaded to connect it to a fitting *j*, which is bored out to permit the lower tube *k* to slide therein. The upper part of the tube *k* has a flange *m*, which is fluted, as

shown in the sectional plan view, Fig. 3, to permit it to slide within the tube *h*, but preventing its rotation. The flexible conductors *c* pass through both tubes to the lamp 5 or other device, the lower end of the tube *k* being connected to such device. To raise and lower the lamp, it suffices to slide the tube *k* within the tube *h*, the conductors *c* being thereby unwound from or rewound 10 upon the reel *b*. To prevent the rotation of the upper tube *h*, whereby the wires *c* might be twisted and strained, a stud *n* is provided, passing through a hole *o* in the socket *f* and screwed in the ball *d*.

15. In cases where the risk of twisting the wires is small the tubes *h* may be cylindrical instead of being fluted.

The fitting *j*, through which the lower tube passes, may be in the form of a packed gland.

20. Although in the preceding figures I have shown the reel mounted within the body *a*, in Fig. 4 I show how the reel *b* may be mounted or inclosed within the ball *d*. The reel in this instance is shown as being a rotary 25 switch made in accordance with my said former patent, although any suitable spring-reel with independent switching mechanism may be used. The bearings for the reel are provided as shown in the ball *d* itself, so that 30 the reel partakes of the same oscillatory movement as the ball. A chain *p*, attached to the ball *d* and the outer casing *g*, prevents the ball *d* and tube *e* from being rotated about their axes except to a limited extent.

35. It will be understood that my invention is applicable not only to a single lamp, but to

electroliers, as indicated in Fig. 5, nor is it limited to lamps pendent from the ceiling; but the fittings may be attached to a wall, as shown in Fig. 6, or carried on a table or floor, 40 as illustrated in Fig. 7.

I declare that what I claim is—

1. In combination in electric fittings, a body or housing, a tube, a ball connected to one end of the tube, an outer casing, a socket 45 for the ball formed partly in the housing and the outer casing, means for binding the ball in the socket and compensating for wear, a spring-actuated reel located above the tube and flexible conductors wound upon the reel 50 and passing through the tube to the lamp or other current-consuming device.

2. In combination in electric fittings a body or housing *a*, a spring-actuated reel contained therein, a tube, a ball carried on the 55 end of such tube, an outer casing *g*, a socket for the ball formed partly in the housing *a* and partly by the casing *g*, means for binding the ball within such socket and compensating for wear, flexible conductors wound 60 upon the spring-reel and passing through the tube to the lamp or other current-consuming device, and a bush of insulating material fitted to the free end of the tube substantially as described.

In testimony whereof I have signed my name to this specification in the presence of two subscribing witnesses.

JOHN DUGDILL.
